SAMUEL BERGSTEIN, OF MIDDLETOWN, OHIO.

MEANS AND METHOD FOR MAKING PAPER TUBES OR THE LIKE.

Application filed May 31, 1927. Serial No. 195,462.

This invention relates to means and methods for making paper tubes, having particular reference to spirally wound paper tubes.

In the accompanying drawings which 5 serve for illustrating the invention in one form:

Fig. 1 is a plan view of a paper tube winding machine with the invention applied thereto;

10 Fig. 2 is a sectional view of the machine on line 2—2 of Fig. 1;

Fig. 3 is a sectional view on line 3—3 of Fig. 1;

15 Fig. 4 is a view of the machine in side elevation;

Fig. 5 is a detail view of the thread defining mechanism;

Fig. 6 is a detail view of the completed tube;

20 Fig. 7 is a detail sectional view of the tube showing the thread formation;

Fig. 8 is a detail view of the reinforcement winding mechanism.

The objects attained in the invention consist in means and method for applying a reinforcing element, as cord or wire, to spirally wound paper tubes, coincident with their formation, the reinforcement serving also, and more especially, as means for applying 25 end caps to the tubes.

30 The means for applying the cord or wire to the tubes, either material being suitable for attaining the objects of the invention, consist in an attachment adapted to be applied to a well known type of spiral paper tube forming machine, which acts to wind the reinforcing element spirally on the tube as the same is being formed, the cord or wire winding attachment being operated at 35 greater speed than the speed at which the tube is rotated in the process of formation, thus acting to effect a spiral of less degree or less lead of the reinforcing element than that of the strips of material from which the tube 40 is formed.

45 The reinforcing element, as herein described, is wound at a suitable lead for effecting a thread on the tube adapted for receiving threaded metal caps for closing the 50 ends of the tubes as the same are cut into suitable lengths for use. The cord or wire, as the case may be, being wound on the tubes under tension, and with an application of adhesive or an outer covering of the tube

material, if desired, the same adheres firmly 55 to the tubes and serves as a reinforcement and end cap retainer for the tubes of relatively great strength.

As the reinforcing element is applied coincident with the formation of the tubes and 60 without slowing down production, only the cost of the reinforcing material is added to the production cost, the small added cost being more than offset by the adaptation of the tubes without further operations or added 65 material for receiving the end caps. The greater strength and durability of the reinforced tubes, having particular reference to the improved method for closing the ends of 70 the tubes, is very desirable in containers of this character, especially in the larger sizes 75 which are used for distributing heavy merchandise, as metal products, etc.

The attachment for applying the reinforcing element is adapted for winding one or 75 more coils of the cord or wire on the tube for effecting a plurality of threads, each having the same lead, thus providing stronger holding means for the end caps which are threaded accordingly. For effecting air-tight sealing 80 of the tubes, the ends of the tubes or the end caps may be given an application of adhesive as the caps are applied.

The thread winding mechanism is here 85 shown as applied to a well known type of spiral paper tube forming machine which, briefly described, comprises a suitable frame structure including opposite rails 1 mounted on legs 2 and having at one end a base plate 3 which carries the spindle 4 to which is secured 90 one end of the mandrel 5 upon which the tube is formed and from which it is delivered as formed, the opposite end of the mandrel being unsupported. Mounted loosely upon spindle 4 are a pair of pulleys 6—7, the 95 pulley 6 being traversed by a belt 8 from a pulley on any suitable drive shaft. The hub of pulley 6 has secured to it a spur gear 9 which meshes with a gear 10 on a stud 11 supported in an arm 12 projecting from the base 100 3. Secured to gear 10 is a gear 13 meshing with a gear 14 on shaft 15 supported in bearings 16. Splined on shaft 15 are bevel gears 17 meshing with bevel gears 18 on the lower 105 ends of vertical shafts 19 supported in bearings 20 mounted on transverse bars 21 which rest on the opposite rails 1 and are provided with depending bolts 22 which pass through

bars 23 bearing against the under sides of rails 1, the bolts being provided with nuts 24 for securing bars 21 in any position to which they have been adjusted longitudinally on 5 rails 1.

Upon each transverse bar 21 is pivotally mounted a swinging bar 25 by means of a bolt 26, the bolts being in line axially with shafts 19. The outer ends of the swinging 10 bars 25 carry clamps 27 engaging with segmental ribs 28 formed on bars 21, the stems of the clamps being threaded and provided with nuts 29 so that the swinging bars 25 can be adjusted on the carrying bars 21 and secured 15 in position after being adjusted.

Guided on ways at the outer ends of the swinging bars 25 are slides 30 having bearings for vertical shafts 31 and also for horizontal shafts 32, the inner ends of the latter 20 having bearings in posts 33 near the inner ends of the swinging bars 25. Each shaft 32 has at its inner end a bevel gear 34 meshing with a bevel gear 18 on a shaft 19, and at its outer end a bevel gear 35 meshing with a bevel 25 gear 36 on the lower end of a shaft 31, the gears 35 being splined on shafts 32 so that the adjustment of the slides 30 on bars 25 can be readily effected.

Each pair of shafts 19—31 carries a pair 30 of belt drums 37—38 traversed by a belt 39 which runs from the right side of one pulley to, over and around the mandrel 5 and thence to the left side of the opposite pulley, the return run of the belt crossing from pulley to 35 pulley above the mandrel, being twisted in its course to clear the mandrel as shown in Fig. 2. That portion of each belt 39 which surrounds the mandrel follows a spiral course, the angle of which is determined by adjustment of 40 pulleys 37—38 angularly one relative to the other, this being effected by swinging bars 21 on bars 25 which carry the outer pulley shafts 31, the shafts 19 constituting the pivot center upon which bars 25 swing in effecting adjustment of the pulleys, thus the adjustment 45 can be made without tightening or slackening belts 39 or stopping the machine.

In order to tighten or slacken the presser 50 belts 39 for adapting them for tubes of different diameters, the slides 30 are adjusted longitudinally on the bars 35 by means of screws having hand wheels 40 in a manner similar to the means employed for adjusting the tool carriages of lathes, etc.

55 A bracket 41 mounted on one of the side rails 1 carries at its upper end a guide 42 for the strip of paper 43 which forms the inner coil of the tube, the strip being wound directly on the mandrel 5. A rod 44 is carried 60 by arms 45 and 46, upon which are mounted guides 47—48 for strips 49—50 which form, respectively, the intermediate and outer coils of the tube which is being produced, these strips being coated with a suitable cement 65 before reaching the machine for effecting ad-

hesion between layers of the material wound on the tube.

The strip 49 is acted on by the first pressure belt 39 and is wound firmly around the inner coil of the tube, the strip 50 being acted 70 on by the second belt 39 and wound in like manner on the intermediate coil of the tube, the finished tube moving from the mandrel to mechanism, not shown, for cutting the same into suitable commercial lengths. 75

The thread winding mechanism comprised in the invention consists of a bracket 51 spanning the rails 1, being provided with a hollow bearing stem 52 for clearing the tube 53 as it moves along the mandrel 5, and serving to 80 support a rotatable member 54 upon which a plurality of spools 55 of cord or wire are supported, the material being drawn off the spools through guides 56—57, suitable means being provided, not shown, in connection 85 with guides 56 for applying tension on the material so that the same will be drawn taut on the tube.

Rotation of the thread winder is effected, as here shown, by a driving connection with 90 gear 10, consisting of a pinion 58 on a shaft 59 and a chain and sprocket connection 60—61—62 between the shaft and the rotatable member 54. The reduction between gears 10—58 and between sprockets 61—62 may be of any 95 suitable degree for effecting the desired lead of the thread on the tube. It will be obvious that single lead threads, or more than two threads, all having the same lead, can be wound on the tube by the arrangement shown 100 without change in the mechanism other than to provide for supporting the required number of spools of thread material and the guides for directing the same to the tube.

The thread winder, as here shown, is interposed between the mechanism for winding the intermediate and outer strips 49—50 of the tube material. Thus the outer strip is wound over the thread. For the purpose of defining the thread on the periphery of the tube, a 110 thread follower is provided, consisting of a bracket 63 spanning rails 1, in which a rotatable sleeve 64 is supported, the sleeve being apertured for clearing the paper tube, and serving to support the pressure devices 65 115 for following the thread and acting to press the outer layer of material between threads into engagement with the intermediate layer of material as illustrated in Figs. 6—7.

A detail of the thread follower is shown in 120 Fig. 5, the mechanism consisting in a pressure wheel 65 supported on an axially adjustable threaded stem 66, the stem being provided with a head 67 and lock nut 68 for effecting the adjustments to regulate the pressure on the tube. The mechanism is operably connected to shaft 59 by a chain and sprocket connection 69—70—71 which serves for driving the mechanism at the same speed of rotation as the thread winding mechanism. 125 130

From the statement of the invention and the foregoing detailed description of one form of the apparatus for applying the same in the manufacture of reinforced spiral paper tubes, the objects attained will be apparent. The effect on the tubes is illustrated in Figs. 6-7, Fig. 7 being an enlarged detail sectional view serving to illustrate the well defined thread which is produced. The thread 56 being covered by the outer layer of material 50 which is cemented to the intermediate layer of material, provides means of relatively great strength for connecting the end caps 53^a which are threaded with suitable allowance made for the thread covering material to prevent tearing of the material as the caps are applied. As stated in the introduction to the detail specification, the ends of the tubes or the inside of the end caps may be given an application of cement for sealing the end caps thus to effect air-tight containers of the tubes.

Having described my invention, I claim:

1. A machine of the character described consisting in means for winding strips of material spirally for forming a tube, the tube being rotated as it is formed, and means comprising a member rotatable around the tube at greater speed than that at which the tube rotates, and serving to support a thread element, as cord or wire, and acting to wind said element with a predetermined lead on the tube.

2. A machine of the character described consisting in means for winding strips of material spirally for forming a tube, means operably coordinated with the strip winding means for winding a thread of cord or wire on the tube between layers of said material and with a different lead than that at which the material is wound, and a follower oper-

able over the outer layer of material for defining the lead of said thread.

3. A machine of the character described including means for winding strips of material spirally for forming a tube, means operably coordinated with the strip winding means for winding a thread of cord or wire on the tube between layers of said material with a different lead than that at which the material is wound, and a follower rotatable around the tube over the outer layer of material for defining the lead of said thread.

4. A machine of the character described including means for winding strips of material spirally for forming a tube, means operably coordinated with the strip winding means for winding a thread of cord or wire on the tube between layers of said material with a different lead than that at which the material is wound, and a follower rotatable around the tube over the outer layer of material at the same speed at which the threadwinder rotates, following the lead of the thread and acting between threads to press the outer material against the adjacent inner layer of material.

5. A machine of the character described consisting in means for winding strips of material spirally for forming a tube, the tube being rotated as it is formed, and means comprising a member rotatable around the tube at greater speed than that at which the tube rotates, and serving to support a thread element, as cord or wire, and acting to wind said element with a predetermined lead on the tube, the lead of the thread being variable with the change of speed of said rotatable member.

In testimony whereof, I affix my signature.

SAMUEL BERGSTEIN.
